(57) **CLAIM**

The ornamental design for a handset, as shown and described.

DESCRIPTION

FIG. 1 is a perspective view of a handset showing our new design;
FIG. 2 is a front view thereof;
FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines showing the environmental structure of the handset and all of the unshaded regions within, including the array of tiny circles at the bottom rear, are for illustrative purposes only and form no part of the claimed design.

1 Claim, 5 Drawing Sheets
